SYNTHESIS OF CYCLOPROPANE

Henry B. Hass, West Lafayette, Ind., and George E. Hinds, Grosse Ile, Mich., assignors to Purdue Research Foundation, West Lafayette, Ind., a corporation of Indiana

No Drawing. Application June 12, 1937,
Serial No. 147,988

10 Claims. (Cl. 260—654)

It is the object of our invention to produce 2-chloropropene from 1,2,2-trichloropropane; and to produce both 2-chloropropene and cyclopropane from a mixture of 1,2,2-trichloropropane 5 and 1,3-dichloropropane.

In the chlorination of propane, as described in the Haas & McBee patents Nos. 2,004,072 and 2,004,073, a mixture containing a number of monochlorides and polychlorides is obtained; for 10 all possible chlorides are produced to a greater or less extent. Among the polychlorides are both the four dichlorides and the various trichlorides.

After the mixture of chlorides has been obtained by chlorinating propane, the various chlorides may be separated, as individuals or in 15 groups, as for example in rectifying columns; in accordance with their boiling points. The various boiling points at standard pressure (760 mm.) appear in the following table:

20 *Monochlorides*

- a. 2 Chloropropane, boils at 34.7° C.
- b. 1 Chloropropane, boils at 46.8° C.

25 *Dichlorides*

- c. 2,2-dichloropropane, boils at 67° C.
- d. 1,1-dichloropropane, boils at 85°-87° C.
- e. 1,2-dichloropropane, boils at 96.8° C.

←1st cut.

30 f. 1,3-dichloropropane, boils at 120.4° C.

Trichlorides

- g. 1,2,2-trichloropropane, boils at 123° C.

←2nd cut.

35 h. Other polychlorides, boil above 132° C.

Fraction f, which is 1,3-dichloropropane, has great utility in the production of cyclopropane, in the manner set forth in our co-pending application Serial No. 717,429, filed March 26, 1934, now patent No. 2,098,239, granted November 9, 1937.

We have found that fraction g, which is 1,2,2-trichloropropane, can be converted into 2-chloropropene by the same general treatment, involving the removing of chlorine atoms from different carbon atoms, that is set forth in our aforesaid co-pending application Serial No. 717,429; save that instead of being a ring-closing reaction to produce cyclopropane, the reaction is one in which the removing of the two chlorine atoms doubles the already existing bond between the carbon atoms (at the 1 and 2 positions) from which said chlorine atoms are removed, to produce the desired 2-chloropropene.

55 In addition, while it is readily possible to sepa-

rate 1,3-dichloropropane from the lower-boiling mono- and di-chlorides a to e inclusive by making a cut between e and f in the foregoing table, and while it is also readily possible to separate 1,2,2-trichloropropane from the higher boiling 5 polychlorides (indicated collectively at h) by making a cut between g and h in said table, as is indicated on such table, it is difficult to get an adequate separation between 1,3-dichloropropane and 1,2,2-trichloropropane—or between f and g 10 in said table—because their boiling points of 120.4° C. and 123° C. are so close together.

Therefore, in fractionating the chlorides, we have discovered that it is convenient and economical to obtain a middle fraction of the mixture of 1,3-dichloropropane and the 1,2,2-trichloropropane, by separating therefrom in a rectifying column (1) the monochlorides and dichlorides a to e which have lower boiling points than has this middle fraction and (2) the polychlorides h which have higher boiling points than has said middle fraction.

If the middle-fraction mixture thus obtained of 1,3-dichloropropane and 1,2,2-trichloropropane is now treated, in the manner set forth in our aforesaid co-pending application Serial No. 717,429, to remove the two chlorine atoms from 1,3-dichloropropane and effect a ring-closure to produce cyclopropane, we have found that the same operation also removes two chlorine atoms from adjacent carbon atoms of the 1,2,2-trichloropropane, and produces a double bond between those two carbon atoms, thus producing 2-chloropropene at the same time that cyclopropane is produced.

The cyclopropane and the 2-chloropropene, thus simultaneously produced, may readily be separated in a rectifying column, because their boiling points are quite far apart. Cyclopropane boils at -32.8° C., while 2-chloropropene boils at 40 +22.6° C.—a difference of 55.4° C. This is many times as great as the difference between the boiling points of 1,3-dichloropropane and 1,2,2-trichloropropane, and is amply sufficient for easy separation in the rectifying column.

Our present invention, therefore, contemplates the process of producing 2-chloropropene from 1,2,2-trichloropropane; and it also contemplates the production of a mixture of cyclopropane and 2-chloropropene from a mixture of 1,3-dichloropropane and 1,2,2-trichloropropane, and the separation of the produced mixture to obtain either or both of its components, cyclopropane and 2-chloropropene.

In carrying out our invention, we may obtain 55

1,2,2-trichloropropane in any desired manner. Also, we may obtain a mixture of 1,3-dichloropropane and 1,2,2-trichloropropane in any desired manner. Desirably we obtain this mixture by 5 chlorinating propane, as for example in the processes set forth in the Hass & McBee patents Nos. 2,004,072 and 2,004,073 already referred to, and separating such mixture from the lower and the higher boiling chlorides that are simultaneously 10 produced, by making a first cut between *e* and *f* in the table given above and a second cut between *g* and *h* in such table.

Having obtained the selected starting material, whether it is 1,2,2-trichloropropane alone or a 15 mixture of 1,3-dichloropropane and 1,2,2-trichloropropane, we then treat it in the general manner set forth in our aforesaid co-pending application Serial No. 717,429.

This is done by causing the 1,2,2-trichloropropane, or the mixture of it with 1,3-dichloropropane, to react with zinc or magnesium or sodium. The following summarizing equations show the reactions when zinc is used:

35 The summarizing equations with magnesium or sodium, or other usable metals, are in general similar.

In order to obtain simultaneously the reactions indicated in equations 1 and 2, whatever the 40 metal used, certain conditions of the reaction should be maintained. These conditions are in general those which are necessary for preparing normal alkyl magnesium chlorides from normal alkyl chlorides and magnesium; in that there 45 must be present substantially no compound containing hydrogen displaceable by the metal used under the conditions employed in the reaction, and that the temperature must be sufficiently 50 high to initiate the reaction. The temperature necessary depends on the metal used, and is highest for zinc and lowest for magnesium for a given 55 reaction rate.

Also in obtaining those two reactions simultaneously, we usually prefer either to use a catalyst to start the reaction or to raise the temperature above the normal boiling point of the 1,3-dichloropropane, or both. If no solvent is used, however, such raising of the temperature involves 60 high-pressure operation and apparatus, which is usually not desired; and therefore we prefer to use a boiling-point-raising solvent which has a boiling point above that of 1,3-dichloropropane. Any such solvent which dissolves trimethylene 65 chloride and 1,2,2-trichloropropane may be used which is suitable for use in preparing the Grignard reagent and which is substantially unattacked by the reagents and/or reaction products under the conditions employed. The most effective groups of solvents are the higher-boiling 70 ethers, such as diphenyl ether and dibutyl ether, and the higher-boiling hydrocarbons, such as biphenyl. We prefer to use no catalyst with either zinc or sodium; but in using magnesium we may 75 use a catalyst instead of or in addition to heat

to initiate the reaction, and in that case we may use a preformed Grignard reagent or any catalyst which is used in preparing the Grignard reagent.

Not all of the above conditions need be maintained, however, if it is desired merely to produce 2-chloropropene from 1,2,2-trichloropropane, as this latter reaction appears to take place with greater facility than the reaction for the preparation of cyclopropane from 1,3-dichloro- 10 propane.

The following are examples of our process:

Example 1: Diphenyl ether, the boiling point of which is 259° C., has a maximum quantity of zinc dust added to it so that the mixture still 15 stirs fairly easily, and a sufficient quantity of either 1,2,2-trichloropropane or a mixture of 1,2,2-trichloropropane and 1,3-dichloropropane to lower the boiling point to the neighborhood of 180° to 210° C. The whole is heated to that boiling 20 point, with stirring, and a gas is evolved which is almost wholly the desired 2-chloropropene if the chloride added was 1,2,2-trichloropropane, and is almost wholly a mixture of 2-chloropropene and cyclopropane if the mixed chlorides 25 (1,2,2-trichloropropane and 1,3-dichloropropane) were the added chlorides. As the gas is evolved, additional 1,2,2-trichloropropane or mixture of 1,2,2-trichloropropane and 1,3-dichloropropane is desirably added, and the boiling point is thus 30 maintained within the range given. The gas evolved is collected. If the added chloride was 1,2,2-trichloropropane alone, this gas is mainly 2-chloropropene. But if the added chlorides were mixed 1,2,2-trichloropropane and 1,3-dichloro- 35 propane, such gas is mainly mixed 2-chloropropene and cyclopropane; and in that case the two components of the mixture are separated by rectification, as is readily possible because of the wide difference between their boiling points, 40 to obtain separately both cyclopropane and 2-chloropropene.

The process of removing the two chlorine atoms by the zinc is continued as long as the reaction 45 proceeds actively; but in time the zinc particles become coated with the zinc chloride which is formed as a by-product, and the reaction gradually slows down. When this occurs, the zinc mass is separated from the solvent, as by decanting or filtering, and washed with any solvent, such as ethyl ether, which dissolves the zinc chloride from the zinc particles; whereupon the cleaned zinc dust may be used again. The zinc chloride, separated as such by evaporation 55 of the ethyl ether, is a valuable by-product.

Example 2: Biphenyl, which boils at 250° C., has from 5% to 10% by weight of metallic sodium added to it, and then enough 1,2,2-trichloropropane, or mixture of 1,2,2-trichloropropane and 1,3-dichloropropane, to reduce the boiling point 60 to the neighborhood of 170° to 200° C. Some reaction occurs at room temperature, although a very slow one; but the reaction may be accelerated by heating, desirably to the boiling point, 65 without danger that it will become too violent. In either instance, slowly in the cold and more rapidly on heating, a gas is evolved which is rich in 2-chloropropene or in mixed 2-chloropropene and cyclopropane according to the starting 70 chloride or chlorides used. If it is a mixture, the two components of it, 2-chloropropene and cyclopropane, can be separated by rectification.

Example 3: *n*-Butyl ether, which boils at 141.7° 75

C., has magnesium turnings or powder added to it, in any desired amount, so long as the amount of solid material either originally present or produced in the reaction is kept sufficiently small to avoid interference with stirring. Then a small amount of 1,2,2-trichloropropane, or of mixed 1,2,2-trichloropropane and 1,3-dichloropropane, is added, usually not to exceed 5%, and the mass heated until boiling occurs. A gas is evolved, which is rich in 2-chloropropene or in mixed 2-chloropropene and cyclopropane, according to the starting chloride or chlorides used. As the reaction proceeds, more of the starting chloride or chlorides may be added, either slowly and continuously or in small increments. After the reaction is going well, the heating may be discontinued, for the reaction is exothermic. If desired, a small amount of a catalyst may be added initially to start the reaction. Suitable catalysts are ethyl iodide or free iodine, or preferably a preformed Grignard reagent.

In all these examples, and especially in examples 2 and 3 where sodium and magnesium are used, it is desirable to maintain rather rigorously anhydrous conditions. This is also desirable when zinc is used, although not so essential; but in any case there should be substantial freedom from water or other substance which contains hydrogen displaceable by the metal used under the conditions employed in the reaction.

A feature of distinction of the process of the present invention to which it is desired to direct attention, is that, somewhat surprisingly, two entirely dissimilar dechlorination reactions take place simultaneously under inherently identical conditions, one involving a ring closure (to form cyclopropane, and thus changing a paraffinic hydrocarbon skeleton to a naphthenic one), and the other involving a direct unsaturation (to form 2-chloropropene, and thus changing a paraffinic hydrocarbon skeleton to an olefinic one). Ordinarily it would be inferred that two such dissimilar reactions would require incompatible, or at least dissimilar, reaction conditions, but our findings lead to an unexpected, contrary conclusion.

The foregoing synthesis of 2-chloropropene by the reaction of zinc with 1,2,2-trichloropropane, and of a mixture of cyclopropane and 2-chloropropene by the reaction of zinc with a mixture of 1,3-dichloropropane and 1,2,2-trichloropropane, may be obtained in the absence of a catalyst if in the presence of certain high-boiling ethers and hydrocarbons, which are compounds containing no hydrogen displaceable by the zinc under the conditions employed in the reaction, and can be made to give fairly good yields. Yet the reaction is somewhat slow, and that slowness has some disadvantages in commercial operations.

We have also found that by varying the procedure somewhat, as will now appear, it is possible to obtain a number of advantages. Among such advantages are an increased speed of reaction, an increased yield of 2-chloropropene or of mixed cyclopropane and 2-chloropropene, a lower temperature of reaction, and the elimination of the necessity of avoiding components containing hydrogen replaceable by zinc.

In the co-pending application filed by us and Earl W. Gluesenkamp, Serial No. 85,048, filed June 13, 1936, it is shown that cyclopropane may be produced by the simple reaction of zinc with

either 1-chloro-3-iodopropane or 1,3-di-iodopropane, by the following reactions:

In that Hass, Hinds & Gluesenkamp application Serial No. 85,048 it was also shown that one or both of the chlorine atoms of 1,3-dichloropropane (trimethylene chloride) may be replaced by iodine by a metathetical reaction with sodium iodide, to yield 1-chloro-3-iodopropane and 1,3-di-iodopropane respectively, as shown by the following reactions:

It was pointed out in that application that suitable solvents for carrying out this reaction are acetone and ethanol; since sodium iodide is soluble in those solvents, while sodium chloride is practically insoluble in them and so when formed is removed from the reaction by precipitation. The reactions shown in equations 5 and 6 may be merely summarizing reactions, and we believe they are; for we believe that what actually happens is that the sodium iodide ionizes to yield free iodide ions which are present in the sodium solution in alcohol, and that it is these iodide ions which react with the 1,3-dichloropropane, as shown by the following equations:

In that Hass, Hinds & Gluesenkamp application Serial No. 85,048 it was also pointed out that it is possible to regenerate sodium iodide, or the iodide ions therefrom, in the reaction, by the use of a much cheaper reagent; so that such sodium iodide takes on the nature of a catalyst rather than a reactant in the total reaction, and only a small quantity of sodium iodide need be used. That regeneration is obtainable by any reagent that is capable of reacting with zinc iodide to yield a more highly ionized iodide; for such a reagent reacts with the zinc chloroiodide or the zinc iodide of equations 3 and 4 to reproduce the iodide ions. Quite a number of reagents will do this, and two simple ones are sodium carbonate and acetamide.

As the result of those things, it was pointed out in said Hass, Hinds & Gluesenkamp application that not only can cyclopropane be produced by the simple reaction of zinc with either 1-chloro-3-iodopropane or 1,3-di-iodopropane as shown in equations 3 and 4, but that in addition it is possible to obtain a rapid production of cyclopropane from 1,3-dichloropropane by first converting the latter into 1-chloro-3-iodopropane and/or 1,3-di-iodopropane by the use of free iodide ions and then reacting the product so obtained with zinc, while at the same time regenerating in the solution the iodide ions to maintain the reaction rate without requiring sodium iodide in more than catalytic amounts.

We have now discovered the surprising fact that similarly the production of 2-chloropropene from 1,2,2-trichloropropane may be made more rapid by the use of free iodide ions, and then re-

acting the products so obtained with zinc, while at the same time regenerating in the solution the iodide ions to maintain the reaction rate without requiring the sodium iodide in more than 5 catalytic amount.

In consequence, since this increase in rapidity occurs both in the production of cyclopropane from 1,3-dichloropropane (as set forth in the aforesaid Hass, Hinds & Gluesenkamp application) and in the production of 2-chloropropene from 1,2,2-trichloropropane, a corresponding 10 rapidity of reaction is obtainable in converting a mixture of 1,3-dichloropropane and 1,2,2-trichloropropane into a mixture of cyclopropane and 15 2-chloropropene.

An example will show the general technique: 20 300 gm. of acetamide, 0.02 mole of sodium iodide, 0.377 mole of sodium carbonate, and 1.1 moles of zinc dust are placed in a 1-liter three-neck round-bottom flask fitted with a mercury-seal stirrer, a dropping funnel, and a reflux condenser in the respective necks. The reflux condenser is connected at the top to an outlet tube leading 25 to the apparatus for collecting the gas. Any suitable means may be used to remove any ammonia which results from the reaction of traces of moisture with the acetamide. A charge of 0.832 mole of 1,2,2-trichloropropane, or of a mixture of 1,3-dichloropropane and 1,2,2-trichloropropane, is placed in the dropping funnel, and admitted to the body of the flask drop by drop over a period of about five hours while the 30 temperature of the flask is maintained at about 125° C.—desirably within 5° of that temperature. The gaseous product which passes from the top 35 of that reflux condenser and is collected in the collecting apparatus is 2-chloropropene if only 1,2,2-trichloropropane was dropped in through the dropping funnel, and is a mixture of cyclopropane and 2-chloropropene if it was a mixture of 1,3-dichloropropane and 1,2,2-trichloropropane which was dropped in through the dropping 40 funnel; in which latter case the two components of the resultant mixture may be separated by 45 rectification as has already been described.

Another example of our invention is as follows: An apparatus is used consisting of a 500 ml. round-bottom three-neck flask, a condenser, and a motor-driven mechanical stirrer. By means of 50 glass tubing, gases are conducted from the top of the condenser into a straight-tube condenser kept in a bath at about -79° C.

This flask is charged with 120 ml. of 75% aqueous ethanol, 0.1 mole of 1,2,2-trichloropropane or of a mixture of 1,3-dichloropropane and 1,2,2-trichloropropane, 0.1 mole of anhydrous sodium carbonate, 0.2 mole of zinc dust, and 1/60 mole of sodium iodide. The flask containing this charge is heated on a steam bath for twelve 55 hours, and crude 2-chloropropene (if only 1,2,2-trichloropropane was used) or a mixture of crude cyclopropane and 2-chloropropene (if a mixture of 1,3-dichloropropane and 1,2,2-trichloropropane was used) is evolved and collected. The gas so obtained is purified in well-known ways; and if it is a mixture of cyclopropane and 2-chloropropene the components of that mixture are separated by rectification.

We claim as our invention:

70 1. The process of producing cyclopropane, which comprises causing a mixture of 1,3-dichloropropane and 1,2,2-trichloropropane to react with a metal exhibiting an affinity for chlorine, to yield a chloride of the metal and a mixture of cyclopropane and 2-chloropropene,

and fractionating to separate cyclopropane from the mixture so obtained.

2. The process of producing cyclopropane and 2-chloropropene, which comprises causing a mixture of 1,3-dichloropropane and 1,2,2-trichloropropane to react with a metal exhibiting an affinity for chlorine, to yield a chloride of the metal and a mixture of cyclopropane and 2-chloropropene, and fractionating the mixture of cyclopropane and 2-chloropropene into its components. 5

3. The process of producing cyclopropane, which consists in causing a mixture of 1,3-dichloropropane and 1,2,2-trichloropropane to react with a metal exhibiting an affinity for chlorine, to yield a chloride of the metal and a mixture of cyclopropane and 2-chloropropene, and subjecting said last-named mixture to rectification to obtain the desired cyclopropane. 10 15

4. The process of preparing cyclopropane, which consists in chlorinating propane to get a mixture of chlorides of propane, subjecting said mixture of chlorides of propane to rectification to separate from lower-boiling fractions and from higher-boiling fractions a middle fraction 20 consisting mainly of 1,3-dichloropropane and 1,2,2-trichloropropane, causing that middle fraction to react with a metal exhibiting an affinity for chlorine to yield a chloride of that metal and a mixture of cyclopropane and 2-chloropropene, 25 and fractionating to separate cyclopropane from that last-named mixture of cyclopropane and 2-chloropropene.

5. The process of producing substantially pure cyclopropane from impure 1,3-dichloropropane 30 that is contaminated with 1,2,2-trichloropropane, which consists in causing said contaminated 1,3-dichloropropane to react with a metal exhibiting an affinity for chlorine to yield a chloride of that metal and a cyclopropane which 35 is contaminated with 2-chloropropene, and subjecting that contaminated cyclopropane to rectification to separate substantially pure cyclopropane therefrom.

6. The process of producing cyclopropane, 40 which comprises causing a mixture of 1,3-dichloropropane and 1,2,2-trichloropropane to react with zinc, to yield zinc chloride and a mixture of cyclopropane and 2-chloropropene, and fractionating to separate cyclopropane from the 45 mixture so obtained.

7. The process of producing cyclopropane and 2-chloropropene, which comprises causing a mixture of 1,3-dichloropropane and 1,2,2-trichloropropane to react with zinc, to yield zinc chloride and a mixture of cyclopropane and 2-chloropropene, 50 and fractionating the mixture of cyclopropane and 2-chloropropene into its components.

8. The process of producing cyclopropane, 55 which consists in causing a mixture of 1,3-dichloropropane and 1,2,2-trichloropropane to react with zinc, to yield zinc chloride and a mixture of cyclopropane and 2-chloropropene, and subjecting said last-named mixture to rectification to obtain the desired cyclopropane.

9. The process of preparing cyclopropane, which consists in chlorinating propane to get a mixture of chlorides of propane, subjecting said mixture of chlorides of propane to rectification to separate from lower-boiling fractions and from higher-boiling fractions a middle fraction 60 consisting mainly of 1,3-dichloropropane and 1,2,2-trichloropropane, causing that middle fraction to react with zinc to yield zinc chloride 70 75

- and a mixture of cyclopropane and 2-chloropropene, and fractionating to separate cyclopropane from that last-named mixture of cyclopropane and 2-chloropropene.
- 5 10. The process of producing substantially pure cyclopropane from impure 1,3-dichloropropane that is contaminated with 1,2,2-trichloropropane, which consists in causing said con-
- taminated 1,3-dichloropropane to react with zinc to yield zinc chloride and a cyclopropane which is contaminated with 2-chloropropene, and subjecting that contaminated cyclopropane to rectification to separate substantially pure 5 cyclopropane therefrom.
